UNITED STATES PATENT OFFICE

135,147

DESIGN FOR A PHONOGRAPH RECORD CABINET

Gilbert W. Amberg, Kankakee, Ill., assignor to Amberg File and Index Company, Kankakee,
Ill., a corporation of Illinois

Application January 4, 1943, Serial No. 109,201

Term of patent 14 years

To all whom it may concern:

Be it known that I, Gilbert W. Amberg, a citizen of the United States, residing at Kankakee, in the county of Kankakee and State of Illinois, have invented a new, original, and ornamental Design for a Phonograph Record Cabinet, of which the following is a specification, reference being had to the accompanying drawing, forming a part thereof.

I claim:

The ornamental design for a phonograph record cabinet, as shown.

GILBERT W. AMBERG.
